(57) **CLAIM**

The ornamental design for a control for a system for electrical treatment of nerves, as shown and described.

DESCRIPTION

FIG. 1 is a front view of the control for a system for electrical treatment of nerves according to the present invention;

FIG. 2 is a rear view thereof;

FIG. 3 is a right side view thereof;

FIG. 4 is a left side view thereof;

FIG. 5 is a bottom view thereof;

FIG. 6 is a top view thereof; and,

FIG. 7 is a perspective view thereof.

The broken lines illustrate portions of the control for a system for electrical treatment of nerves which form no part of the claimed design.

1 Claim, 5 Drawing Sheets
